UNITED STATES PATENT OFFICE.

ROBERT PARK McMAHAN, OF PITTSBURGH, PENNSYLVANIA.

INDICATOR.

1,303,699.

Specification of Letters Patent. Patented May 13, 1919.

Application filed January 6, 1919. Serial No. 269,913.

To all whom it may concern:

Be it known that I, ROBERT PARK McMAHAN, a citizen of the United States, residing at Pittsburgh, in the county of Allegheny and State of Pennsylvania, have invented new and useful Improvements in Indicators, of which the following is a specification.

This invention relates to an indicator and more particularly to an indicator to be used on vehicles whereby a party may have visible indications as to whom the vehicle belongs, its number, and other data that may be advisable to know about the vehicle.

An object of the invention is to provide simple means normally inactive but rendered active upon looking into the interior of the device for illuminating and displaying the data relating to the vehicle.

With these and other objects in view the invention will be better understood from the following detailed description taken in connection with the accompanying drawing wherein:

Figure 1 is a longitudinal sectional view through the invention.

Fig. 2 is a front elevation of the card and its holder.

Again referring to the drawing illustrating one form that my invention may assume, the numeral 1 designates a casing having a lateral extension 2 forming a sight passage 3. Arranged within the casing at one end of the sight passage 3 is a simplified form of card holder 4, the card 5 supported thereby by having printed thereon any data found necessary to be displayed. For instance, if the device is used on automobiles this card may have marked thereon, the following:—

“John Doe; Engine No. 81356; License No. Penna. 6781459”.

Of course it is to be understood that the card 5 may display any information found necessary. The remaining end of the passage 3 is normally closed by a cover or door 6 pivotally mounted as indicated at 7 and held closed by the weighted arm 8. By applying pressure to the arm or finger piece 8, the door 6 may be thrown to open position and when in open position I have arranged an electric circuit adapted to be energized automatically upon the door reaching its fully open position.

The illuminating means shown in the drawing consist of a bulb 9 arranged within the casing preferably directly behind the card 5 and is arranged in a circuit 10 which may include the generator 11 of the vehicle and has one terminal grounded on the casing as indicated at 12 and the other end connected to a contact 13 insulated from the casing in the path of movement of the door 6.

From the foregoing description taken in connection with the accompanying drawing it will be seen that a person by operating the arm 8 may throw the door 6 to open position and through its engagement with the contact 13 automatically illuminate the bulb 9 so that the data on the card 5 may be clearly viewed through the passage 3.

It is of course to be understood that the apparatus may be constructed in various other manners than shown and may be permanently attached to the vehicle in any manner found suitable and besides if found advantageous in practice the rear wall 14 of the casing may be hinged to the casing and locked thereto by a suitable padlock 15, so that different cards may be placed within the holder 4.

Having described my invention, what I claim is:

1. An indicator comprising a casing having a laterally extending sight passage, a display card arranged within the casing at one end of the sight passage, a door normally closing the other end of the sight passage and electric means rendered active upon opening of said door to view said card.

2. An indicator comprising a casing having a lateral extension forming a sight passage, a display card mounted within the casing at one end of said passage, illuminating means for the casing including a contact arranged adjacent the other end of the passage and a normally closed cover for the last mentioned end of the passage arranged with relation to said contact so that the latter will be engaged when the cover is thrown to open position for rendering the illuminating means active.

In testimony whereof I affix my signature.

ROBERT PARK McMAHAN.
